UNITED STATES PATENT OFFICE

GIUSTINO CATTANEO, OF MILAN, ITALY

AIR COOLING OF THE CYLINDERS OF INTERNAL COMBUSTION ENGINES

Application filed March 28, 1928, Serial No. 265,486, and in Italy March 28, 1927.

The main difficulty in connection with the air cooling of the cylinders of internal combustion engines having a plurality of aligned cylinders, that is to say arranged one behind the other on an axis parallel to the direction of the current of the cooling air, lies in the fact that the foremost cylinder is struck by the air current in full, whereas the following cylinders are each masked by the preceding cylinder or cylinders and are licked, on a small portion only of their outer sides, by the air that has been heated by contact with the cooling ribs of the preceding cylinders. The consequence is that the temperature of the various cylinders increases as they are farther away from the foremost cylinder and may attain values that may render the running of the engines difficult or even impossible owing to the loss of viscosity or owing to the combustion of the lubricating oil, both of which inconveniences entail friction, wear and seizing of the pistons and breakages of the valves and especially of the exhaust valves which become overheated.

The object of the present invention is to secure, in the engines having their cylinders arranged in star or fan form with large front surface, a uniform cooling for each cylinder by supplying to each of them an appropriate amount of air at the same temperature, the air being conveyed to each cylinder independently from the other cylinders through separate ducts, so that it reaches the individual cylinder to which it is destined and is guided at will during its travel.

The accompanying drawings illustrate the invention as applied to a 12 cylinder engine, the cylinders being arranged in two rows of six cylinders each forming a V of 60° opening and being provided with the usual cooling ribs. It will be noticed that, as far as the cooling is concerned, each cylinder row is completely independent, so that the system is applicable to engines having any number of cylinder rows.

Fig. 1 is a front elevation of an internal combustion engine illustrating the invention applied thereto.

Fig. 2 is a diagrammatic horizontal sectional view of Fig. 1 showing the arrangement and location of the partitions dividing the air conduit into a plurality of channels for directing the cooling air.

Figs. 3 and 4 are views corresponding to Figs. 1 and 2 and showing a modification of the invention.

With reference to Figs. 1 and 2, the numerals 1, 2, 3, etc. indicate the cylinders, which are shown in section.

The arrow F indicates the direction of the cooling air current, which may be generated either by an ordinary fan or by the travelling motion of the engine in the surrounding air, as is the case on an aeroplane. The front section of the air current is divided into several streams by the partition walls or guides A, B, C, D, etc. made of sheet metal or other suitable sheet material. These secondary streams of appropriate section are each so guided as to strike the cooling ribs and external surface of the respective cylinder and to act on as great a portion thereof and as uniformly as practicable.

Whilst in Figs. 1 and 2 the said partition walls are located inside of the V, in Figs. 3 and 4 they are located outside of it.

In this manner all cylinders find themselves, in respect to cooling, in the same conditions as the foremost cylinder 1. This will ensure a uniform temperature in all cylinders, because all of them will receive the same amount of air at a uniform initial temperature and under the same inlet and outlet conditions. The current of air, lying outside of the V in the case of Figs. 1 and 2 and lying inside the V in the case of Figs. 3 and 4, will cause a depression at S and therewith assist in sucking in air.

Having now particularly described and ascertained the nature of my said invention and in what manner the same is to be performed, I declare that what I claim is:

In an internal combustion engine, two rows of engine cylinders, an air conduit extending along the side walls of the cylinders of each row and having an air inlet at its forward end, a plurality of partitions arranged in each conduit and dividing the latter into a plural-

ity of channels, said partitions extending laterally between the rows and terminating in parallel relation to the side walls of adjacent cylinders in the same row and defining outlets for the air disposed in proximity to the side walls of the cylinders.

5 Signed at Milan (Italy), this 25th day of Feb., 1928.

GIUSTINO CATTANEO.
